**METHOD OF CONTROLLING A
HYDRAULIC ACTUATOR, A HYDRAULIC
ACTUATOR, A HYDRAULIC SYSTEM AND A
WORKING MACHINE**

**CROSS REFERENCE TO RELATED
APPLICATIONS**

This application is a 35 U.S.C. § 371 national stage application of PCT International Application No. PCT/EP2019/073256 filed on Aug. 30, 2019, the disclosure and content of which is incorporated by reference herein in its entirety.

TECHNICAL FIELD

The invention relates to a method of controlling a hydraulic actuator, a hydraulic actuator, a hydraulic system comprising a hydraulic actuator and a working machine comprising a hydraulic actuator and/or a hydraulic system.

The invention is applicable on hydraulic actuators of working machines within the fields of industrial construction machines, material handling machines or construction equipment, in particular wheel loaders and excavators. Although the invention will be described with respect to an excavator, the invention is not restricted to this particular machine, but may be used in any working machine, such as wheel loaders, articulated or rigid haulers and backhoe loaders.

BACKGROUND

Hydraulic systems are used in a wide range of applications. For example, working machines typically rely on hydraulic systems to provide power for handling loads. A hydraulic system for a working machine may comprise various hydraulic actuators, for example hydraulic cylinders and rotary hydraulic machines. Hydraulic cylinders may for example be provided in a working device comprising arms and a bucket. Rotary hydraulic machines may for example be used for propulsion of a working machine and/or for a swing function of an excavator. Hydraulic hybrid systems can be used to recuperate energy from the hydraulic actuators and use it later to reduce the loading of an internal combustion engine.

Hydraulic systems comprising a dedicated high-pressure side and a dedicated low-pressure side may be referred to as dual pressure hydraulic systems, and are previously known as such. Dual pressure hydraulic systems typically comprise one or more high-pressure accumulators connected to a high-pressure side, and one or more low-pressure accumulators connected to a low-pressure side. Advantages associated with dual pressure hydraulic systems are for example improved energy efficiency and controllability.

A hydraulic cylinder comprising more than two working chambers having effective areas with a binary relationship is previously known. Such hydraulic cylinder may for example comprise four working chambers with an effective area relationship of 8:4:2:1. In case each working chamber is selectively connected to either the high-pressure side or the low-pressure side of a hydraulic system by means of a valve arrangement, the hydraulic cylinder constitutes a digital hydraulic cylinder having 16 discrete force states or pressurization states. When the largest working chamber of such hydraulic cylinder transitions between the high-pressure side and the low-pressure side in order for the hydraulic cylinder to transition between pressurization states 8 and 9,

2

all other working chambers transition as well. The transition of a working chamber between the high-pressure side and the low-pressure side is however associated with transition losses, typically throttling losses and compressibility losses.

5 The transition losses are highest for transitions of the largest working chamber. Transition losses are also high if all working chambers are simultaneously switched between the high-pressure side and the low-pressure side.

SUMMARY

An object of the invention is to provide a method of controlling a hydraulic actuator, which method is energy efficient, accurate, simple and/or cheap, an energy efficient, simple and/or cheap hydraulic actuator, and/or an energy efficient, simple and/or cheap hydraulic system.

According to a first aspect of the invention, the object is achieved by a method of controlling a hydraulic actuator according to claim 1. The method is carried out with a hydraulic actuator comprising a linear double-acting output member, and at least three working chambers in fluid connection with the output member, the working chambers having respective effective areas with a non-binary relationship. The method comprises selectively fluidly connecting each working chamber to either a high-pressure side or a low-pressure side to provide a plurality of discrete pressurization states of the hydraulic actuator. The method further comprises determining at least one of the pressurization states as a prevented pressurization state; and transitioning between a plurality of allowed pressurization states among the pressurization states while preventing transition to the at least one prevented pressurization state.

By means of the non-binary relationship between the 35 respective effective areas of the working chambers, the force output of the output member while maintaining the largest working chamber connected to the high-pressure side can be lower in comparison with a binary coded hydraulic actuator. By preventing transition to at least one prevented pressurization state in a hydraulic actuator comprising working chambers having respective effective areas with a non-binary relationship, the number of transitions of working chambers between the high-pressure side and the low-pressure side can be reduced, and the energy efficiency can 40 be improved, while still providing substantially the same force output performance. In particular, the number of transitions of the working chamber having the largest effective area between the high-pressure side and the low-pressure side can be reduced or eliminated. This in turn 45 reduces transition losses in the hydraulic actuator and thereby increases energy efficiency.

Among the working chambers, at least two of the chambers may be arranged to generate opposite forces on the output member when connected to the high-pressure side. In 50 addition to the non-binary relationship between the respective effective areas of the working chambers, each working chamber may have a unique effective area.

For a hydraulic actuator comprising four working chambers, there are 16 discrete pressurization states, and for a 55 hydraulic actuator comprising three working chambers, there are eight discrete pressurization states. During operation of the hydraulic actuator, the hydraulic actuator adopts one of the pressurization states, i.e. an allowed pressurization state, providing a certain force output in the output member. In case a different force output is requested, a connection to one or more of the working chambers may be 60 switched between the high-pressure side and the low-pres-

sure side. By switching at least one of the working chambers, a different pressurization state is adopted by the hydraulic actuator.

Before transitioning to a different pressurization state, at least one pressurization state is categorized or determined as a prevented pressurization state, where a transition to each prevented pressurization states is prevented. Each of the remaining pressurization states may be determined as an allowed pressurization state, or it may be assumed that each pressurization state not determined as a prevented pressurization state is an allowed pressurization state. The method may comprise transitioning to the pressurization state among the allowed pressurization state that provides a force output that most closely matches a target force output of the output member. Thus, each allowed pressurization state is a candidate pressurization state to which the hydraulic actuator can transition, while each prevented pressurization state is not.

When at least one of the pressurization states is determined as a prevented pressurization state, the hydraulic actuator may be said to be controlled in a selective control.

According to one example, the selective control of the hydraulic actuator is always active during operation of the hydraulic actuator. According to a further example, the selective control of the hydraulic actuator can be manually activated and deactivated, e.g. by means of a user input, such as via a display inside a cab of a working machine. Thus, the hydraulic actuator does not always need to be controlled in the selective control. According to a further example, the selective control of the hydraulic actuator can be automatically activated and deactivated, for example based on an operating condition of the hydraulic actuator, a hydraulic system and/or a working machine. The operating condition may for example include a certain boom position of a working machine, one or more points of a work cycle of a working machine, and/or a currently adopted pressurization state by the hydraulic actuator. The selective control may for example be active when lowering a boom of a working machine with an empty bucket, and inactive when lowering a boom with a heavy-loaded bucket.

The pressurization states may be put in order based on a respective force output of the output member in each pressurization state (for the same pressures in the high-pressure side and the low-pressure side). Thus, a lowest pressurization state is the pressurization state generating the lowest force output in the output member and the highest pressurization state is the pressurization state generating the highest force output in the output member. Correspondingly, two pressurization states having most closely matching force output in the output member are said to be immediately adjacent pressurization states. Except for the lowest pressurization state and the highest pressurization state, each pressurization state has two immediately adjacent pressurization state (one "on each side"), i.e. one that generates the same or least lower force output and one that generates the same or least higher force output. Furthermore, two allowed pressurization states having most closely matching force output in the output member are said to be immediately adjacent allowed pressurization states, although a prevented pressurization state may be provided between these two immediately adjacent allowed pressurization states.

In case the hydraulic actuator comprises four working chambers, pressurized hydraulic fluid in the largest working chamber and in the third largest working chamber may generate a force output of the output member in one direction (e.g. in an extending direction), and pressurized hydraulic fluid in the second largest working chamber and in the

smallest working chamber may generate a force output of the output member in an opposite direction (e.g. in a retracting direction). In case the hydraulic actuator comprises only three working chambers, pressurized hydraulic fluid in the largest working chamber and in the smallest working chamber may generate a force output of the output member in one direction (e.g. in an extending direction), and pressurized hydraulic fluid in the second largest working chamber may generate a force output of the output member in an opposite direction (e.g. in a retracting direction). Thus, in comparison with a four-chamber hydraulic actuator, the fourth and smallest working chamber may be omitted for a three-chamber hydraulic actuator. The hydraulic actuator may also comprise more than four working chambers, such as five or six working chambers.

According to one embodiment, the method is carried out in a hydraulic system comprising a high-pressure side, a low-pressure side, and a valve arrangement arranged to selectively fluidly connect each working chamber to either the high-pressure side or the low-pressure side to provide the plurality of discrete pressurization states of the hydraulic actuator.

Since the valve arrangement is arranged to selectively fluidly connect each working chamber to either the high-pressure side or the low-pressure side to provide a plurality of discrete pressurization states of the hydraulic actuator, the hydraulic actuator is a digital hydraulic actuator. The valve arrangement may be arranged to selectively fluidly connect each working chamber to either the high-pressure side or the low-pressure side independently of the remaining working chambers. The valve arrangement may comprise a plurality of valves, for example one or two valves associated with each working chamber. Each valve may be a proportional valve. Alternatively, each valve may be an on/off valve. When each valve is either fully open or fully closed, a plurality of discrete force states or pressurization states are provided for constant pressures in the high-pressure side and in the low-pressure side.

The high pressure in the high-pressure side is higher than the low pressure in the low-pressure side during operation of the hydraulic system. The pressures in the high-pressure side and the low-pressure side are not limited to any specific pressure values. Rather, the terminologies "high pressure" and "low pressure" indicate that these pressure levels are different and that the high pressure is higher than the low pressure. The pressure levels in the high-pressure side and the low-pressure side are selected depending on each configuration. The pressure levels in the high-pressure side and the low-pressure side may vary during operation of the hydraulic system.

The high-pressure side may be referred to as a primary side or primary source of hydraulic power arranged to both produce and receive a volume flow at a first pressure level and the low-pressure side may be referred to as a secondary side or secondary source of hydraulic power arranged to both produce and receive a volume flow at a second pressure level, lower than the first pressure level.

According to one embodiment, at least two of the working chambers have respective effective areas with a substantially binary relationship, or binary relationship. According to one example, the area relationship is 8:3:2:1 or 7:3:2:1. Each of these area relationships provides two force output plateaus, for pressurization states 4 and 5 and for pressurization states 12 and 13. According to a further example, the area relationship is 6:3:2:1. This area relationship provides three

force output plateaus, for pressurization states 4 and 5, pressurization states 8 and 9, and pressurization states 12 and 13.

With a substantially binary relationship, the effective area of the second smallest working chamber may deviate less than 20%, such as less than 15%, such as less than 10%, such as less than 5%, from twice the effective area of the smallest working chamber. Alternatively, or in addition, with a substantially binary relationship, the effective area of the third smallest working chamber may deviate less than 20%, such as less than 15%, such as less than 10%, such as less than 5% from four times the effective area of the smallest working chamber.

According to one embodiment, the hydraulic actuator comprises at least four working chambers, and at least three of the working chambers have respective effective areas with a substantially binary relationship, or binary relationship. In this case, a working chamber other than the at least three working chambers may have the largest effective area.

The non-binary relationship of the respective effective areas of the working chambers may for example be 6-8:3-5:1.5-2.5:0.5-1.5, such as 6.5-7.0:3.9-4.1:1.9-2.1:0.95-1.05, such as 6.5-7:4:2:1. According to one example, the area relationship is 7:4:2:1. With this area relationship, the force output is the same in pressurization states 8 and 9. Thus, pressurization states 8 and 9 provide a plateau in terms of force output. According to a further example, the area relationship is 6.5:4:2:1. With this area relationship, the force output step size between pressurization states 7-10, is half the force output step size between pressurization states 1-7 and 10-16. According to a further example, the area relationship is 6:4:2:1. This area relationship provides two force output plateaus, for pressurization states 7 and 8, and pressurization states 9 and 10.

The effective areas of a hydraulic actuator comprising at least three working chambers having a non-binary relationship may refer to the effective area of at least one of the working chambers having a non-binary relationship to the effective areas of at least some of the effective areas of the other working chambers. The effective areas of the other working chambers may or may not have a binary relationship to one another.

According to one embodiment, the hydraulic actuator comprises at least four working chambers, and the fourth smallest effective area is 2.75-3.75 times the second smallest effective area. In this case, the three smallest effective areas or the two smallest effective areas may have a substantially binary relationship, or binary relationship. Alternatively, or in addition, the largest effective area may be 2.75-3.75 times the third largest effective area.

According to one embodiment, the hydraulic actuator may comprise at least four working chambers, and the fourth smallest effective area may be 6-7.5 times the smallest effective area. Also in this case, the three smallest effective areas or the two smallest effective areas may have a substantially binary relationship, or binary relationship. Alternatively, or in addition, the largest effective area may be 6-7.5 times the fourth largest effective area. For example, the non-binary relationship of the respective effective areas of the working chambers may be 6-8:3-5:1.5-2.5:0.5-1.5, such as 6.5-7.0:3.9-4.1:1.9-2.1:0.95-1.05, such as 6.5-7:4:2:1.

According to one embodiment, the pressurization states are put in order based on a respective force output of the output member in each pressurization state, and the method further comprises switching less than all working chambers between the high-pressure side and the low-pressure side when transitioning from each allowed pressurization state to

an immediately adjacent allowed pressurization state. Thus, the hydraulic actuator can sequentially transition through all allowed pressurization states without having to simultaneously switch all working chambers. In this way, transition losses can be further reduced.

According to one embodiment, the pressurization states are put in order based on a respective force output of the output member in each pressurization state, and the method further comprises transitioning between two of the allowed pressurization states by skipping one or more of the at least one prevented pressurization state. In some situations, the method may thus comprise transitioning to a pressurization state that does not most closely match a target force output. However, by switching to an allowed pressurization state that is close enough to the target force output, excessive high-pressure/low-pressure transitions for one or more working chambers can be avoided. The force output can then be made to accurately match the target force output by throttling through the valve arrangement.

For example, during a force decrease of the output member, the force of the output member may be controlled to decrease by transitioning from a relatively high allowed pressurization state to a relatively low allowed pressurization state by skipping an intermediate prevented pressurization state, wherein for constant pressures in the high-pressure side and the low-pressure side, the intermediate prevented pressurization state corresponds to an intermediate force in the output member, the relatively high allowed pressurization state corresponds to a relatively high force in the output member, and the relatively low allowed pressurization state corresponds to a relatively low force in the output member; and wherein the intermediate force is higher than, or equal to, the relatively low force, and the intermediate force is lower than, or equal to, the relatively high force.

The determination of at least one pressurization state as a prevented pressurization states may be static or dynamic. According to one embodiment, the method further comprises determining one or more of the at least one prevented pressurization state in dependence of a currently adopted pressurization state. In this way, the categorization of the pressurization states is made dynamic.

According to one embodiment, the method further comprises determining one or more of the at least one prevented pressurization state in dependence of whether the working chamber having the largest effective area is connected to the high-pressure side or the low-pressure side. In this way, a hysteresis effect can be introduced which further reduces transition losses associated with the working chamber having the largest effective area. Also this categorization of the at least one prevented pressurization state is dynamic.

Thus, the at least one prevented pressurization state when the working chamber having the largest effective area is connected to the high-pressure side may be different from the at least one prevented pressurization state when the working chamber having the largest effective area is connected to the low-pressure side. For example, when the working chamber having the largest effective area is connected to the high-pressure side, the allowed pressurization states may comprise all pressurization states where the working chamber having the largest effective area is connected to the high-pressure side. Conversely, when the working chamber having the largest effective area is connected to the low-pressure side, the allowed pressurization states may comprise all pressurization states where the working chamber having the largest effective area is connected to the low-pressure side.

According to one embodiment, the method further comprises determining one or more of the plurality of allowed pressurization states in dependence of whether the working chamber having the largest effective area is connected to the high-pressure side or the low-pressure side.

According to one embodiment, the method further comprises determining one or more of the plurality of allowed pressurization states and/or one or more of the at least one prevented pressurization state in dependence of whether the working chamber having the second largest effective area is connected to the high-pressure side or the low-pressure side. In this way, a hysteresis effect can be introduced which further reduces transition losses associated with the working chamber having the second largest effective area. For example, at least one prevented pressurization state when the working chamber having the second largest effective area is connected to the high-pressure side may be different from at least one prevented pressurization state when the working chamber having the second largest effective area is connected to the low-pressure side.

According to one embodiment, the working chamber having the largest effective area is connected to the high-pressure side in each allowed pressurization state, or the working chamber having the largest effective area is connected to the low-pressure side in each allowed pressurization state. Thus, the working chamber having the largest effective area may be connected to the same of one of the high-pressure side and the low-pressure side in each pressurization state of the allowed pressurization states.

For example, if the working chamber having the largest effective area is connected to the high-pressure side in each allowed pressurization state in a hydraulic actuator having four working chambers with an area coding or area relationship of 7:4:2:1, each of pressurization states 9-16 is allowed and each of pressurization states 1-8 are prevented. In this way, transition of the working chamber having the largest effective area is prevented and the energy recovery is very high.

As a further example, if the working chamber having the largest effective area is connected to the low-pressure side in each allowed pressurization state in a hydraulic actuator having four working chambers with an area relationship of 7:4:2:1, each of pressurization states 1-8 is allowed and each of pressurization states 9-16 are prevented. In this way, transition of the working chamber having the largest effective area is prevented and the acceleration is not limited by the categorization of pressurization states.

According to one embodiment, the pressurization states are put in order based on a respective force output of the output member in each pressurization state, and for constant pressures in the high-pressure side and the low-pressure side, a difference between a force output of the output member in one of the allowed pressurization states and a force output of the output member in one of the prevented pressurization states, is smaller than a difference between force outputs of the output member in two immediately adjacent allowed pressurization states.

According to one embodiment, for constant pressures in the high-pressure side and the low-pressure side, a force output of the output member in one of the allowed pressurization states and a force output of the output member in one of the prevented pressurization states are the same, or substantially the same (e.g. less than 5% difference). Thus, two or more pressurization states can produce the same or substantially the same force output while having different pressurizations of the working chambers. This enables operation of the hydraulic actuator in a larger force output

range without having to switch connection of a certain working chamber between the high-pressure side and the low-pressure side. Thereby, an energy efficient control of the hydraulic actuator can be made more versatile since more often, acceptable acceleration of the output member can be reached without switching the largest working chamber. Although the other working chambers do transitions, these transitions have less impact on energy efficiency since the involved area and volume under transition are smaller.

10 According to one embodiment, the pressurization states are put in order based on a respective force output of the output member in each pressurization state, and for constant pressures in the high-pressure side and the low-pressure side, a difference between a force output of the output member in one of the allowed pressurization states and a force output of the output member in an immediately adjacent prevented pressurization state, is less than 70%, such as less than 50%, such as less than 45% of a difference between a force output of the output member in the one of 15 the allowed pressurization states and a force output of the output member in an immediately adjacent allowed pressurization state.

According to a second aspect, the object is achieved by a hydraulic actuator. The hydraulic actuator comprises a linear double-acting output member; and at least three working chambers in fluid connection with the output member, the working chambers having respective effective areas with a non-binary relationship. At least two of the working chambers have respective effective areas with a substantially 20 binary relationship, or binary relationship.

According to one embodiment, the hydraulic actuator comprises at least four working chambers, and the fourth smallest effective area is 2.75-3.75 times the second smallest effective area. Alternatively, or in addition, the largest effective area may be 2.75-3.75 times the third largest effective area.

According to one embodiment, the hydraulic actuator comprises at least four working chambers, and the fourth smallest effective area is 6-7.5 times the smallest effective area. Alternatively, or in addition, the largest effective area may be 6-7.5 times the fourth largest effective area.

According to one embodiment, the hydraulic actuator comprises at least four working chambers having respective effective areas with a non-binary relationship; and two of the working chambers have respective effective areas with a substantially binary relationship, or binary relationship. Examples of such area relationships are 8:3:2:1, 7:3:2:1 and 6:3:2:1.

According to one embodiment, the hydraulic actuator comprises at least four working chambers, and at least three of the working chambers have respective effective areas with a substantially binary relationship, or binary relationship. In this case, a working chamber other than the at least three working chambers may have the largest effective area. Examples of such area relationships are 7:4:2:1, 6.5:4:2:1 and 6:4:2:1.

According to a third aspect, the object is achieved by a hydraulic system. The hydraulic system comprising a hydraulic actuator having a linear double-acting output member, and at least three working chambers in connection with the output member, the working chamber have respective effective areas with a non-binary relationship; a high-pressure side; a low-pressure side; a valve arrangement arranged to selectively fluidly connect each working chamber to either the high-pressure side or the low-pressure side to provide a plurality of discrete pressurization states of the hydraulic actuator; and a control system configured to

control the hydraulic actuator by controlling the valve arrangement. The control system is configured to determine at least one of the pressurization states as a prevented pressurization state; and control the hydraulic actuator to transition between a plurality of allowed pressurization states among the pressurization states while preventing transitioning to the at least one prevented pressurization state.

The control system preferably comprises a control unit. The control unit may include a microprocessor, microcontroller, programmable digital signal processor or another programmable device. The control unit may also, or instead, include an application specific integrated circuit, a programmable gate array or programmable array logic, a programmable logic device, or a digital signal processor. Where the control unit includes a programmable device such as the microprocessor, microcontroller or programmable digital signal processor mentioned above, the processor may further include computer executable code that controls operation of the programmable device.

According to one embodiment, at least two of the working chambers have respective effective areas with a substantially binary relationship, or binary relationship. Examples of such area relationships are 8:3:2:1, 7:3:2:1, 6:3:2:1, 7:4:2:1, 6.5:4:2:1 and 6:4:2:1.

According to one embodiment, the hydraulic actuator comprises at least four working chambers having respective effective areas with a non-binary relationship; and two of the working chambers have respective effective areas with a substantially binary relationship, or binary relationship. Examples of such area relationships are 8:3:2:1, 7:3:2:1 and 6:3:2:1.

According to one embodiment, the hydraulic actuator comprises at least four working chambers, and at least three of the working chambers have respective effective areas with a substantially binary relationship, or binary relationship. In this case, the working chamber other than the at least three working chambers may have the largest effective area. Examples of such area relationships are 7:4:2:1, 6.5:4:2:1 and 6:4:2:1.

The invention also relates to a hydraulic system configured to carry out a method according to the present invention.

The invention also relates to a working machine comprising a hydraulic actuator according to the invention and/or a hydraulic system according to the invention. The working machine may be a material handling machines or a construction machine, in particular a wheel loader or an excavator.

Further advantages and advantageous features of the invention are disclosed in the following description.

BRIEF DESCRIPTION OF THE DRAWINGS

With reference to the appended drawings, below follows a more detailed description of embodiments of the invention cited as examples.

In the drawings:

FIG. 1 is a schematic illustration of a working machine according to the invention comprising a hydraulic system, FIG. 2 is a block diagram of the hydraulic system in FIG. 1,

FIG. 3a is a partial block diagram of the hydraulic system showing a hydraulic actuator and a valve arrangement,

FIG. 3b is a diagram showing a force output of an output member for a plurality of pressurization states of the hydraulic actuator in FIG. 3a,

FIG. 4a is a partial block diagram of the hydraulic system showing a further example of hydraulic actuator and a valve arrangement,

FIG. 4b is a diagram showing a force output of an output member for a plurality of pressurization states of the hydraulic actuator in FIG. 4a, and

FIG. 5 is a flowchart outlining the general steps of the method according to the invention.

DETAILED DESCRIPTION OF EXAMPLE EMBODIMENTS OF THE INVENTION

In the following, a method of controlling a hydraulic actuator, a hydraulic actuator, a hydraulic system comprising a hydraulic actuator and a working machine comprising a hydraulic actuator and/or a hydraulic system, will be described. The same or similar reference numerals will be used to denote the same or similar structural features.

FIG. 1 is a schematic illustration of a working machine 18 according to the invention. The working machine 18 comprises a hydraulic system 20 according to the invention. The working machine 18 is exemplified as an excavator. The working machine 18 comprises an upper swing structure 22, a lower travel structure 24 and a working device 26. The working machine 18 further comprises a cab 28 in the upper swing structure 22, and a swing motor 30 between the upper swing structure 22 and the lower travel structure 24. The lower travel structure 24 comprises two travel motors 32 (only one is visible in FIG. 1) for driving a respective crawler track.

The working device 26 comprises a boom 34, an arm 36 and a bucket 38. The working device 26 further comprises two hydraulic actuators 40 (only one is visible in FIG. 1) exemplified as boom cylinders, a hydraulic actuator 42 exemplified as an arm cylinder and a hydraulic actuator 44 exemplified as a bucket cylinder. The hydraulic actuators 40 operate between the upper swing structure 22 and the boom 34 by means of a linear double-acting output member 46. The hydraulic actuator 42 operates between the boom 34 and the arm 36 by means of a linear double-acting output member 46. The hydraulic actuator 44 operates between the arm 36 and the bucket 38 by means of a linear double-acting output member 46. In this example, each output member 46 is a piston rod.

FIG. 2 is a block diagram of the hydraulic system 20 in FIG. 1 according to an embodiment of the invention. The hydraulic system 20 comprises a high-pressure side 48 and a low-pressure side 50. In the example in FIG. 2, the high-pressure side 48 and the low-pressure side 50 are arranged in a common pressure rail (CPR) architecture. The high-pressure side 48 comprises a high-pressure rail and the low-pressure side 50 comprises a low-pressure rail. The high-pressure side 48 and the low-pressure side 50 may alternatively be referred to as a high-pressure circuit and a low-pressure circuit, respectively. The high-pressure side 48 and the low-pressure side 50 form a dual pressure system comprising two charging circuits at different pressure levels (the high-pressure side 48 and the low-pressure side 50). The hydraulic system 20 thus comprises a dedicated high-pressure side 48 and a dedicated low-pressure side 50. The dual pressure hydraulic system 20 differs from load sensing hydraulic systems where pressure is to a substantially larger extent adjusted depending on load, i.e. a resistive control.

During operation of the hydraulic system 20, the pressure in the high-pressure side 48 is higher than the pressure in the low-pressure side 50. These pressure levels may vary somewhat during operation of the hydraulic system 20 while the

11

pressure in the high-pressure side **48** is higher than the pressure in the low-pressure side **50**. The high pressure in the high-pressure side **48** may for example be 200-350 bars $\pm$ 10%, such as 250 bars $\pm$ 10%, during operation of the hydraulic system **20**. The low pressure in the low-pressure side **50** may for example be 15-30 bars $\pm$ 10% during operation of the hydraulic system **20**. The high pressure in the high-pressure side **48** may for example be 330 bars when the hydraulic actuators **40** are in a low position and 200 bars when the hydraulic actuators **40** are in a high position.

The hydraulic system **20** further comprises a high-pressure hydraulic energy storage **52** and a low-pressure hydraulic energy storage **54**. The high-pressure hydraulic energy storage **52** is connected to the high-pressure side **48** and the low-pressure hydraulic energy storage **54** is connected to the low-pressure side **50**. In FIG. 2, each of the high-pressure hydraulic energy storage **52** and the low-pressure hydraulic energy storage **54** is exemplified as an accumulator. The high-pressure hydraulic energy storage **52** can store/release hydraulic energy from/to the high-pressure side **48**. The low-pressure hydraulic energy storage **54** can store/release hydraulic energy from/to the low-pressure side **50**. The high-pressure hydraulic energy storage **52** requires a higher energy storage capacity in case the pressure variation in the high-pressure side **48** is low and vice versa. The same applies for the low-pressure hydraulic energy storage **54** with respect to the low-pressure side **50**.

The hydraulic system **20** further comprises a main pump **56**. In FIG. 2, the main pump **56** is connected to the high-pressure side **48** and the low-pressure side **50**. The main pump **56** is arranged to pressurize the high-pressure side **48**. The main pump **56** is here exemplified as a variable displacement hydraulic machine operative as both pump and motor.

The hydraulic system **20** further comprises an auxiliary pump **58**. In the example in FIG. 2, the auxiliary pump **58** is arranged to supply pressurized fluid from a tank **60** to the high-pressure side **48**. The auxiliary pump **58** of this example is a fixed displacement pump. The main pump **56** and the auxiliary pump **58** are connected to a common drive shaft driven by an internal combustion engine **62** of the working machine **18**.

The hydraulic system **20** of this example further comprises a pressure relief valve **64** connected between the low-pressure side **50** and the tank **60**. The hydraulic system **20** further comprises a fan motor **66**, and a fan **68** arranged to be driven by the fan motor **66**.

The hydraulic system **20** further comprises three variable displacement hydraulic machines **70**, **72**. The hydraulic machine **70** is arranged to rotationally drive the swing motor **30** and each of the two hydraulic machines **72** is arranged to rotationally drive a respective travel motor **32**.

The hydraulic system **20** further comprises three gearboxes **74**. One gearbox **74** is arranged between a hydraulic machine **70** and the swing motor **30**, and one gearbox **74** is arranged between each hydraulic machine **72** and a respective travel motor **32**. Each gearbox **74** is driven by a drive shaft **76** of a respective hydraulic machine **70**, **72**.

The hydraulic system **20** further comprises a plurality of valve arrangements **78**, **80**. Each valve arrangement **78** is associated with one of the hydraulic actuators **40**, **42**, **36**. One valve arrangement **80** is associated with the swing motor **30** and one valve arrangement **80** is associated with each travel motor **32**. Each valve arrangement **78**, **80** is in fluid communication with the high-pressure side **48** and the low-pressure side **50**.

12

The hydraulic system **20** further comprises a control system **82**. The control system **82** comprises a data processing device and a memory having a computer program stored thereon, the computer program comprising program code which, when executed by the data processing device causes the data processing device to perform various steps, or command execution of various steps, as described herein.

FIG. 3a is a partial block diagram of the hydraulic system **20** showing one of the hydraulic actuators **40** and the associated valve arrangement **78**. One, several or each of the hydraulic actuators **40**, **42** may be of the same design as in FIG. 3a. The hydraulic actuator **40** comprises four variable volume working chambers **84-A**, **84-B**, **84-C**, **84-D**, i.e. a first working chamber or "A-chamber" **84-A**, a second working chamber or "B-chamber" **84-B**, a third working chamber or "C-chamber" **84-C** and a fourth working chamber or "D-chamber" **84-D**. Each working chamber **84-A**, **84-B**, **84-C**, **84-D** may also be referred to with reference numeral "84".

The working chambers **84** in FIGS. 3a and 3b have respective effective areas with a non-binary relationship of 6.5:4:2:1. Thus, the first working chamber **84-A** has an effective area that is 6.5 times the effective area of the fourth working chamber **84-D**, the second working chamber **84-B** has an effective area that is four times the effective area of the fourth working chamber **84-D**, and the third working chamber **84-C** has an effective area that is two times the effective area of the fourth working chamber **84-D**. Although the four working chambers **84** have effective areas with a non-binary relationship, the second working chamber **84-B**, the third working chamber **84-C** and the fourth working chamber **84-D** have a binary relationship of 4:2:1.

The valve arrangement **78** is configured to selectively fluidly connect each working chamber **84** to either the high-pressure side **48** or the low-pressure side **50**. Thereby, the hydraulic actuator **40** can adopt 16 discrete pressurization states. The valve arrangement **78** of this example comprises eight proportional valves **86-A**, **86-B**, **86-C**, **86-D**, **88-A**, **88-B**, **88-C**, **88-D**. Each valve **86-A**, **86-B**, **86-C**, **86-D** may also be referred to with reference numeral "86" and each valve **88-A**, **88-B**, **88-C**, **88-D** may also be referred to with reference numeral "88".

The valve **86-A** is provided between the high-pressure side **48** and the first working chamber **84-A**, the valve **88-A** is provided between the low-pressure side **50** and the first working chamber **84-A**, the valve **86-B** is provided between the high-pressure side **48** and the second working chamber **84-B**, the valve **88-B** is provided between the low-pressure side **50** and the second working chamber **84-B**, the valve **86-C** is provided between the high-pressure side **48** and the third working chamber **84-C**, the valve **88-C** is provided between the low-pressure side **50** and the third working chamber **84-C**, the valve **86-D** is provided between the high-pressure side **48** and the fourth working chamber **84-D**, and the valve **88-D** is provided between the low-pressure side **50** and the fourth working chamber **84-D**. Although the proportional valves **86**, **88** provide 16 discrete pressurization states in the hydraulic actuator **40**, hydraulic fluid may be throttled into or out from each working chamber **84** by means of an associated valve **86**, **88** to alter the discrete force output. The throttling however generates losses.

Transition losses occurs when switching a connection to any of the working chambers **84** between the high-pressure side **48** and the low-pressure side **50**. The highest transition losses occur when transitioning the first working chamber

84-A between the high-pressure side **48** and the low-pressure side **50** since the first working chamber **84-A** has the largest effective area.

FIG. 3b is a diagram showing a force output **90** (in kN) of the output member **46** for a plurality of pressurization states 1-16 of the hydraulic actuator **40** in FIG. 3a. The pressurization states 1-16 are also referred to with reference numeral “**92**”. The two hydraulic actuators **40** of the working machine **18** may have an offset in force to increase the force resolution from 16 discrete force levels to 32 discrete force levels.

When the first working chamber **84-A** is fluidly connected to the high-pressure side **48**, the pressure within the first working chamber **84-A** generates a force on the output member **46** in an extending direction (to the right in FIG. 3a). When the second working chamber **84-B** is fluidly connected to the high-pressure side **48**, the pressure within the second working chamber **84-B** generates a force on the output member **46** in a retracting direction (to the left in FIG. 3a). When the third working chamber **84-C** is fluidly connected to the high-pressure side **48**, the pressure within the third working chamber **84-C** generates a force on the output member **46** in the extending direction. When the fourth working chamber **84-D** is fluidly connected to the high-pressure side **48**, the pressure within the fourth working chamber **84-D** generates a force on the output member **46** in the retracting direction.

As shown in FIG. 3b, the pressurization states 1-16 are put in order based on the corresponding force output **90**. Pressurization state 1 provides the lowest force output **90** (a negative force output **90**) and pressurization state 16 provides the highest force output **90** etc.

A negative force output **90** may for example be required for “return to dig”, i.e. in order to rapidly accelerate the boom **34** downwards with an empty bucket **38**. If the force that the hydraulic actuator **40** can produce while maintaining the first working chamber **84-A** connected to the high-pressure side **48** is not low enough, the first working chamber **84-A** may need to be switched to the low-pressure side **50**.

With the non-binary area relationship of 6.5:4:2:1 of the working chambers **84**, the step size (i.e. the difference in force output **90**) between pressurization states 7-8, 8-9, and 9-10 is half of the step size between pressurization states 1-2, 2-3, 3-4, 4-5, 5-6, 6-7, 10-11, 11-12, 12-13, 13-14, 14-15 and 15-16. Furthermore, in comparison with a binary coded hydraulic actuator, the hydraulic actuator **40** in FIGS. 3a and 3b can produce lower force outputs **90** while maintaining the first working chamber **84-A** connected to the high-pressure side **48**. Thereby, energy recovery by means of the high-pressure hydraulic energy storage **52** can be improved.

In the method of controlling the hydraulic actuator **40**, at least one of the pressurization states **92** is determined as a prevented pressurization state to which the hydraulic actuator **40** is prevented from transitioning. Each of the remaining pressurization states **92** is an allowed pressurization state to which the hydraulic actuator **40** is allowed to transition. In order to provide a target force output **90** in the output member **46**, the hydraulic actuator **40** may be controlled to transition to the allowed pressurization state associated with a force output **90** that most closely matches the target force output **90**, while preventing transition to any of the at least one prevented pressurization state.

The target force output **90** may for example be calculated base on target position, target speed and/or target acceleration of the output member **46**, e.g. by means of the control

system **82**. The control system **82** may control the valve arrangement **78** to switch pressurization of at least one of the working chambers **84** in order to effect a transition of the hydraulic actuator **40** between two pressurization states **92**.

5 The control system **82** may also contain various logic functions for determining which pressurization state **92** that is/are currently prevented, e.g. given certain operating conditions of the hydraulic actuator **40** and/or of the working machine **18**, a certain operating pattern and/or a posture of the working machine **18**.

To accelerate the boom **34** (see FIG. 1) downwards, the force output **90** of the output member **46** is reduced. If the force output **90** that the hydraulic actuator **40** can produce while maintaining the first working chamber **84-A** in fluid connection with the high-pressure side **48** is not low enough for the requested acceleration, the first working chamber **84-A** will transition from the high-pressure side **48** to the low-pressure side **50**. A further transition of the first working chamber **84-A** may occur when a target velocity is reached and the acceleration becomes close to zero.

According to one example, pressurization state 9 is prevented when the hydraulic actuator **40** adopts any of pressurization states 8 or 10-16, i.e. when the first working chamber **84-A** is connected to the high-pressure side **48**. If 15 the control system **82** determines that the force output **90** of pressurization state 9 would be most suitable, the control system **82** may instead command a transition to pressurization state 8 since pressurization state 9 is prevented. Although the force output **90** of pressurization state 8 does not give an as good force match as pressurization state 9, the energy costly depressurization of the first working chamber **84-A** will be avoided. When transitioning from any of 20 pressurization states 8 or 10-16 to an adjacent pressurization state among the allowed pressurization states 1-8 or 10-16, less than all working chambers **84** are switched between the high-pressure side **48** and the low-pressure side **50**. For example, when transitioning from pressurization state 10 to 25 pressurization state 8, pressurization state 9 is skipped and only the fourth working chamber **84-D** is switched.

30 In this example, a difference between the force outputs **90** of the allowed pressurization state 10 and the prevented pressurization state 9 is smaller than a difference between the force outputs **90** of, for example, the immediately adjacent pressurization states 10 and 11. Furthermore, a difference between the force outputs **90** of the allowed 35 pressurization state 10 and the immediately adjacent prevented pressurization state 9 is approximately 50% of the difference between the force outputs **90** of the immediately adjacent allowed pressurization states 10 and 11.

Furthermore, pressurization state 8 is prevented when the hydraulic actuator **40** adopts any of pressurization states 1-7 or 9, i.e. when the first working chamber **84-A** is connected to the low-pressure side **50**. When transitioning from any of 40 pressurization states 1-7 or 9 to an adjacent pressurization state among the allowed pressurization states 1-7 or 9-16, less than all working chambers **84** are switched between the high-pressure side **48** and the low-pressure side **50**. For example, when transitioning from pressurization state 7 to 45 pressurization state 9, pressurization state 8 is skipped and only the fourth working chamber **84-D** is switched.

In this example, a difference between the force outputs **90** of the prevented pressurization state 8 and the allowed 50 pressurization state 7 is smaller than a difference between the force outputs **90** of, for example, the immediately adjacent pressurization states 1 and 2. Furthermore, a difference between the force outputs **90** of the prevented pressurization state 8 and the immediately adjacent pressur-

15

ization state 7 is 50% of the difference between the force outputs **90** of the immediately adjacent allowed pressurization states 6 and 7.

In the above two examples, the plurality of allowed pressurization states and the at least one prevented pressurization state are determined in dependence of whether the first working chamber **84-A** is connected to the high-pressure side **48** or to the low-pressure side **50**. Moreover, the plurality of allowed pressurization states and the at least one prevented pressurization state are different when the first working chamber **84-A** is connected to the high-pressure side **48** and when the first working chamber **84-A** is connected to the low-pressure side **50**.

FIG. **4a** is a partial block diagram of the hydraulic system **20** showing a further example of hydraulic actuator **40** and a valve arrangement **78**. One, several or each of the hydraulic actuators **40, 42** may be of the same design as in FIG. **4a**. FIG. **4b** is a diagram showing a force output **90** of an output member **46** for a plurality of pressurization states **92** of the hydraulic actuator **40** in FIG. **4a**. With collective reference to FIGS. **4a** and **4b**, mainly differences with respect to FIGS. **3a** and **3b** will be described.

The working chambers **84** in FIGS. **4a** and **4b** have respective effective areas with a non-binary relationship of 7:4:2:1. Although the four working chambers **84** have effective areas with a non-binary relationship, the second working chamber **84-B**, the third working chamber **84-C** and the fourth working chamber **84-D** have a binary relationship of 4:2:1.

As can be seen in FIG. **4b**, the force output **90** of the output member **46** is the same in pressurization states 8 and 9. According to one example, pressurization state 8 is prevented when the hydraulic actuator **40** adopts any of pressurization states 9-16. Thus, if a force output **90** corresponding to pressurization states 8 and 9 is requested when the first working chamber **84-A** is connected to the high-pressure side **48**, pressurization state 9 will be selected since pressurization state 8 is prevented. In this way, transition of the first working chamber **84-A** from the high-pressure side **48** to the low-pressure side **50** is avoided. If a force output **90** close to the force output **90** of pressurization state 7 or lower is requested, the hydraulic actuator **40** transitions from any of pressurization states 9-16 to any of pressurization states 1-7 while skipping pressurization state 8.

According to the same example, pressurization state 9 is prevented when the hydraulic actuator **40** adopts any of pressurization states 1-8. Thus, if a force output **90** corresponding to pressurization states 8 and 9 is requested when the first working chamber **84-A** is connected to the low-pressure side **50**, pressurization state 8 will be selected since pressurization state 9 is prevented. In this way, transition of the first working chamber **84-A** from the low-pressure side **50** to the high-pressure side **48** is avoided. If a force output **90** close to the force output **90** of pressurization state 10 or higher is requested, the hydraulic actuator **40** transitions from any of pressurization states 1-8 to any of pressurization states 10-16 while skipping pressurization state 9. Thus, pressurization state 8 is skipped during force decrease and pressurization state 9 is skipped during force increase. In this way, a hysteresis is introduced in the control of the hydraulic actuator **40**, which reduces the number of switches of working chambers **84** between the high-pressure side **48** and the low-pressure side **50** and improves energy efficiency.

FIG. **5** is a flowchart outlining the general steps of the method according to the invention. The method comprises selectively fluidly connecting S1 each working chamber **84** to either a high-pressure side **48** or a low-pressure side **50** to

16

provide a plurality of discrete pressurization states **92** of the hydraulic actuator **40**; determining S2 at least one of the pressurization states **92** as a prevented pressurization state; and transitioning S3 between a plurality of allowed pressurization states among the pressurization states **92** while preventing transition to the at least one prevented pressurization state. Step S2 may be carried out before and/or after step S1.

It is to be understood that the present invention is not limited to the embodiments described above and illustrated in the drawings; rather, the skilled person will recognize that many changes and modifications may be made within the scope of the appended claims.

15 The invention claimed is:

1. A method of controlling a hydraulic actuator, wherein the hydraulic actuator comprises:
a linear double-acting output member, and
at least three working chambers in fluid connection with
the output member, the working chambers having
respective effective areas with a non-binary relation-
ship;

wherein the method comprises:
selectively fluidly connecting each working chamber to
either a high-pressure side or a low-pressure side to
provide a plurality of discrete pressurization states of
the hydraulic actuator;
characterized in that the method further comprises
determining at least one of the pressurization states as a
prevented pressurization state; and
transitioning between a plurality of allowed pressuriza-
tion states among the pressurization states while pre-
venting transition to the at least one prevented pressur-
ization state.

2. The method according to claim 1, wherein the method is carried out in a hydraulic system comprising:

a high-pressure side,
a low-pressure side, and
a valve arrangement arranged to selectively fluidly con-

nect each working chamber to either the high-pressure
side or the low-pressure side to provide the plurality of
discrete pressurization states of the hydraulic actuator.

3. The method according to claim 1, wherein at least two of the working chambers have respective effective areas with a substantially binary relationship.

4. The method according to claim 1, wherein the hydraulic actuator comprises at least four working chambers, and wherein the fourth smallest effective area is 2.75-3.75 times the second smallest effective area.

5. The method according to claim 1, wherein the hydraulic actuator comprises at least four working chambers, and wherein the fourth smallest effective area is 6-7.5 times the smallest effective area.

6. The method according to claim 1, wherein the pres-
surization states are put in order based on a respective force
output of the output member in each pressurization state, and
wherein the method further comprises switching less than all
working chambers between the high-pressure side and the
low-pressure side when transitioning from each allowed
pressurization state to an immediately adjacent allowed
pressurization state.

7. The method according to claim 1, wherein the pres-
surization states are put in order based on a respective force
output of the output member in each pressurization state, and
wherein the method further comprises transitioning between
two of the allowed pressurization states by skipping one or
more of the at least one prevented pressurization state.

17

8. The method according to claim 1, further comprising determining one or more of the at least one prevented pressurization state in dependence of a currently adopted pressurization state.

9. The method according to claim 1, wherein the pressurization states are put in order based on a respective force output of the output member in each pressurization state, and wherein for constant pressures in the high-pressure side and the low-pressure side, a difference between a force output of the output member in one of the allowed pressurization states and a force output of the output member in one of the prevented pressurization states, is smaller than a difference between force outputs of the output member in two immediately adjacent allowed pressurization states.

10. The method according to claim 1, wherein for constant pressures in the high-pressure side and the low-pressure side, a force output of the output member in one of the allowed pressurization states and a force output of the output member in one of the prevented pressurization states are substantially the same.

11. A hydraulic system comprising:

a hydraulic actuator having a linear double-acting output member, and at least three working chambers in connection with the output member, the working chamber have respective effective areas with a non-binary relationship;

a high-pressure side;

a low-pressure side;

a valve arrangement arranged to selectively fluidly connect each working chamber to either the high-pressure side or the low-pressure side to provide a plurality of discrete pressurization states of the hydraulic actuator; and

a control system configured to control the hydraulic actuator by controlling the valve arrangement; characterized in that the control system is configured to: determine at least one of the pressurization states as a prevented pressurization state; and

control the hydraulic actuator to transition between a plurality of allowed pressurization states among the

18

pressurization states while preventing transitioning to the at least one prevented pressurization state.

12. The hydraulic system according to claim 11, wherein at least two of the working chambers have respective effective areas with a substantially binary relationship.

13. The hydraulic system according to claim 11, wherein the hydraulic actuator comprises at least four working chambers having respective effective areas with a non-binary relationship; and wherein two of the working chambers have respective effective areas with a substantially binary relationship.

14. The hydraulic system according to claim 11, wherein the hydraulic actuator comprises at least four working chambers, and wherein at least three of the working chambers have respective effective areas with a substantially binary relationship.

15. A working machine comprising a hydraulic system comprising:

a hydraulic actuator having a linear double-acting output member, and at least three working chambers in connection with the output member, the working chamber have respective effective areas with a non-binary relationship;

a high-pressure side;

a low-pressure side;

a valve arrangement arranged to selectively fluidly connect each working chamber to either the high-pressure side or the low-pressure side to provide a plurality of discrete pressurization states of the hydraulic actuator; and

a control system configured to control the hydraulic actuator by controlling the valve arrangement; characterized in that the control system is configured to: determine at least one of the pressurization states as a prevented pressurization state; and

control the hydraulic actuator to transition between a plurality of allowed pressurization states among the pressurization states while preventing transitioning to the at least one prevented pressurization state.
